Ivan E. C. Ronigsberg

UNITED STATES PATENT OFFICE.

JENS S. LINDHOLM, OF BROOKLYN, NEW YORK.

SIDEWALK-ELEVATOR DOOR.

1,210,817.

Specification of Letters Patent.

Patented Jan. 2, 1917.

Original application filed September 22, 1915, Serial No. 51,923. Divided and this application filed February 15, 1916. Serial No. 78,366.

To all whom it may concern:

Be it known that I, JENS S. LINDHOLM, a citizen of the Danish Monarchy, and resident of Brooklyn, in the county of Kings 5 and State of New York, have invented certain new and useful Improvements in Sidewalk-Elevator Doors, of which the following is a specification.

This invention relates to improvements in 10 sidewalk elevator doors and the object of the invention is to provide means for preventing accidental and untimely opening of the doors for covering the elevator shaft below the sidewalk.

More specifically the invention provides 15 means for automatically closing the sidewalk doors when and as the elevator descends below the sidewalk and whereby the doors remain closed when the elevator is 20 wholly below the sidewalk level. At the same time the means referred to does not prevent the doors from being opened partially by raising the elevator a slight distance above the sidewalk to admit light and 25 air to the space below the same.

This application is a division of my allowed application Serial Number 51,923, filed September 22, 1915.

With the above and other objects in view 30 the invention is embodied in a mechanism arranged and constructed as hereinafter set forth and claimed and as illustrated in the accompanying drawing in which—

Figure 1 is a sectional view of a sidewalk 35 elevator equipped with a door mechanism embodying this invention. Figs. 2, 3 and 4 are enlarged detail views of the parts shown in Fig. 1. Fig. 5 is a detail view showing a modified construction employed when the 40 elevator travels a relatively great distance below the sidewalk.

Referring to the drawing 10 represents the elevator which may be of any well known construction having the frame work 18 and 45 the bow irons 19. The elevator moves in the shaft 13 and 21 represents the hoisting apparatus. The shaft 13 is generally closed by the sidewalk doors 14 and 15 pivoted at 16. In order to compel the doors to close 50 when the elevator descends there are provided in the shaft 13 the sheaves 40, 41, 42 and 43. The rope 44 secured to the door 14 passes over the sheaves 40 and 41, and the rope 45 secured to the door 15 passes 55 over the sheaves 42 and 43. The two ropes

are joined in one rope 46 to which there is yieldingly secured a weight 47 which moves in guides 48 secured to the wall of the shaft.

To the bottom of the weight 47, which serves to keep the ropes taut, there is pivoted 60 a dog 49 having a tail piece 50. When the doors are open the position of the dog 49 is as shown in Fig. 4. After the descent of the elevator and when the doors begin to close, the lower end of the bow iron 18 strikes 65 the dog and pulls the weight 47 down with the door ropes, thereby compelling the doors to follow the bow of the irons and close, the tail piece of the dog sliding against the guide 48 as shown in Fig. 4. When the 70 doors have closed the dog will have reached a recess 51 in the wall of the shaft 13 into which the tail piece 50 will slide and the dog will turn on its pivot 53 as shown in Fig. 2. The dog will now remain in this position 75 during the further continued descent of the elevator as is obvious, because the bow iron slides against the dog and consequently the doors cannot open until on the ascent of the elevator the lower end of the bow iron passes 80 above the dog and when the upper end of the iron strikes the doors pulls the dog out of the recess and permits the weight and the dog to rise. In case the shaft is longer than 85 the height of the bow iron, there will be provided a second or more dogs 54 in the well connected by a link 55 to the upper dog as shown in Fig. 5 and whereby the dogs will remain turned downward and the doors 90 closed during the descent of the elevator.

From the foregoing it is clear that the doors remain closed while the elevator is below the sidewalk and cannot be accidentally opened. Also that the doors open and close 95 with the movements of the elevator and that the length of the travel of the latter is immaterial with respect to the operation of the door closing and locking mechanism.

The invention is susceptible of changes and modifications and I claim all variations, changes and modifications which properly come within the principle of the invention and the scope of the appended claims.

I claim:—

1. The combination with a sidewalk elevator shaft and sidewalk doors therefor, an elevator movable within said shaft and means operated by said elevator for preventing accidental opening of the said sidewalk doors.

105

110

2. The combination with a sidewalk elevator shaft and sidewalk doors therefor, and means including the elevator operated in said shaft for preventing the said doors from being opened by means other than the said elevator and for closing the said doors when the elevator descends.
3. The combination with a sidewalk elevator shaft and sidewalk doors therefor, an elevator operated the length of said shaft, means on said elevator for opening the said

doors on the ascent of the elevator, and means in said shaft and connected to the said doors for closing the latter by the said elevator as it descends and for maintaining said doors closed during the entire descending movement of the elevator below the sidewalk level.

Signed at New York, in the county of New York and State of New York, this 20 14th day of February A. D. 1916.

JENS S. LINDHOLM.
